DES. 1909

Henry G. Thompson, of New York, N.Y.

Assignor to

The Hartford Carpet Company, Hartford, Conn.

Letters Patent No. 1909 Dated March 8th 1864.

Design for a Carpet Pattern.

The schedule referred to in these Letters Patent and making part of the same.

To all whom it may concern:

Be it known that I, Henry G. Thompson, of the City, County and State of New-York, have invented or produced a new and original Design for a Pattern to be inwrought into two-ply Ingrain and other Carpeting, in colors similar to those painted on the drawings accompanying this specification, or in other colors substituted in the place of those painted on the drawings herewith: and I do hereby declare that the drawings accompanying this specification, do give and convey to any one skilled in the Art of Carpet weaving a more defined and thorough description of the nature of my invention than it is in the power of language otherwise to convey, and is sufficient to enable any one skilled in the art of carpet weaving to use my invention.

What I claim as my invention, and desire to secure by Letters Patent, is the configuration of the Design hereunto annexed, when made by being inwrought into two-ply Ingrain or other carpeting, in the form similar to the drawings accompanying this specification.
